Primary Examiner — Karen S Acker

(57) **CLAIM**

The ornamental design for a flag holder, as shown and described.

DESCRIPTION

FIG. 1 is a perspective view of a flag holder showing my new design in a position of use;

FIG. 2 is an enlarged perspective view of a flag holder;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown on the figures are for illustrative purposes only and are hereby disclaimed as forming no part of Applicant's claimed invention.
